UNITED STATES PATENT OFFICE

2,588,878

SCREEN PRINTING APPARATUS

Wallace M. Reemelin, Berkeley, and Roger W. Olmsted, San Francisco, Calif., assignors to Foster and Kleiser Company, San Francisco, Calif.

Application September 16, 1946, Serial No. 697,294

2 Claims. (Cl. 101—123)

1 This invention relates to screen printing apparatus of the type used for printing by the silk screen process, and has for one of its objects the provision of apparatus for effecting a more rapid printing than heretofore, particularly where relatively large sheets are printed, such as each of the sheets used on large bill boards to make up the large poster.

Another object of the invention is the provision of screen printing apparatus that facilitates the positioning and removal of the sheets that have been imprinted as well as the printing, and with the minimum amount of labor.

A still further object of the invention is the provision of screen printing apparatus that is arranged and adapted to enable one workman to position and remove the relatively long sheets from the elongated rectangular printing base of the apparatus from one of the longitudinally extending sides of such base while a single workman at one of the ends of the apparatus actuates the squeegee in one direction or the other in direction longitudinally of the base and printing frame, the latter generally corresponding in shape with the printing base.

In screen printing apparatus, the screen or printing frame and printing base therebelow are usually oblong in plan view and are positioned horizontally. The frame, heretofore, has generally been hinged along one of its longitudinally extending edges to the base, and therefore the paper or material to be printed must be positioned and removed from some one or more of the three remaining sides when the printing frame is swung open. Inserting or removing the paper from the one longitudinally extending side that is opposite the printing frame hinges is awkward where long sheets of paper are being printed inasmuch as two operators must insert the elongated sheets, one being at either end of the latter, and the operator that positions the sheets must work from the same side of the apparatus to adjust the sheets so they will register correctly with the screen or previously printed color. If the sheets are inserted and removed from opposite ends of the frame, it is obvious that the time for removal is longer than were the sheets removed from one side, and also much greater space is required.

Also, heretofore it has been customary in larger screen printing apparatus to require two operators to operate the squeegee, the latter being drawn from end to end of the screen frame. One operator is at each side of the frame. The squeegee is removed from the frame after each printing to enable the frame to swing open.

2 With the present invention, one man at one side of the apparatus positions and removes the paper, and the paper is removed from the side of the frame opposite the operator. Also, only one man at one end of the apparatus is required to operate the squeegee and the squeegee remains in position on the printing frame after each operation. In addition to these advantages, the printing frame and printing base are moved relative to each other to and from closed position by means of fluid pressure, which merely requires the opening and closing of a valve, whereas in prior apparatus, the operators have been required to manually swing the frame away from the printing base. When it is considered that the printing frame must be of rugged construction and on large apparatus is about four feet wide and twelve feet long for printing 34 by 84 inch sheets, it is manifest that the manual swinging of the frame takes time and effort even though each such frame is usually counterbalanced.

Other objects and advantages will appear in the description and in the drawings.

In the drawings:

25 Fig. 1 is a side elevational view showing the apparatus with the printing frame and printing base together and the squeegee about midway between the ends of the printing frame. A portion of the frame is broken away adjacent one end to show structure otherwise concealed.

Fig. 2 is a plan view of the printing base only, with the supporting posts and braces indicated in dash lines.

35 Fig. 3 is a side elevational view of the base of Fig. 2, one of the telescoping posts being broken away and indicated in section.

Fig. 4 is an enlarged fragmentary sectional view taken along the line 4—4 of Fig. 2.

Fig. 5 is a schematic view of the fluid pressure system connected with the extensible telescopic supports for the printing base.

40 Fig. 6 is an enlarged part elevational and part sectional view of one of several identical elevating means for automatically elevating the squeegee at opposite ends of its movement.

Fig. 7 is an elevational view of the printing frame without the squeegee.

50 Fig. 7(a), is a fragmentary semi-diagrammatic view illustrating the take-off roller and conveyor for removing the printed matter from the printing base, a portion of the latter being shown.

Fig. 8 is a top plan view of the squeegee on the printing frame, only enough of the latter being shown to identify it. The handle on the squeegee is in section.

Fig. 9 is an enlarged sectional view taken along line 9-9 of Fig. 8.

Fig. 10 is an enlarged sectional view along line 10-10 of Fig. 8.

Fig. 11 is an enlarged, part sectional and part elevational view through one of the collapsible pneumatically actuated supports for the base frame.

Fig. 12 is an enlarged, fragmentary sectional view of part of the squeegee and printing frame.

Fig. 13 is an enlarged view as seen from line 13-13 of Fig. 12.

Fig. 14 is a diagrammatic, simplified plan view of the printing apparatus and a portion of the conveyor belt.

In detail, a rigid, horizontal printing frame 1 is supported on legs 2 elevated a substantial distance above the floor 3. This frame is usually oblong in plan view, and in the present invention a platform 4 is at one end of the frame and at about the same level. Stairs or a ladder 5 may be provided for the squeegee operator 6 to climb to and descend from the platform. Usually the platform has an extension 7 along one side of the frame for said operator to walk from one end of the frame to the other, and a railing 8 may also be provided for safety reasons.

In Fig. 14 a diagrammatic plan view of the arrangement is shown, and in said view it will be seen that the stack or supply 9 of paper to be printed is at the end of the printing frame opposite platform 4, while a take-off roller 10 is along one longitudinally extending edge of the frame. A conveyor 11 extends away from the take-off roller for carrying the printed sheets through or under a drier that does not form a part of this invention and that is not shown. The operator that positions the sheet to be printed and that removes it after the printing operation, stands at about position 12. It is to be understood that the take-off roller 10 and conveyor 11 are all at about the level of the printing frame, as will later be described more in detail.

The printing base, or what would, in conventional screen printing constitute the stationary table, is indicated at 13, and is below the printing frame.

This base 13 is supported at its four corners on telescopically extensible and collapsible tubular legs, generally designated 14, which legs are extended by pneumatic pressure to different levels as will later be explained. In Fig. 1 the full line position of the printing base indicates its uppermost position, while the dash line position 15 indicates the intermediate working position being somewhere around 35 or 40 inches from the floor. There is a third or lowermost position (Fig. 3) in which the legs are fully collapsed to their limit, and in which the printing base is about half way between position 15 and the floor. When in this latter position there is adequate space between the printing base and the printing frame to facilitate work by an operator on the lower side of the screen or stencil attached thereto, or any other work that requires more working space than is permitted by the space between position 15 in Fig. 1 and the full line position of the printing frame.

The legs 14 each comprises an outer cylinder 20, intermediate cylinder 21, and inner cylinder 22 (Fig. 11). These may all be hollow, although the inner cylinder may be solid.

The outer cylinder 20 is provided with a lower head 23 through which an air pressure line 24 opens into said cylinder. An upper head 25 is

secured to the upper end of said cylinder said head being centrally apertured for reciprocation of intermediate cylinder therethrough, the latter having a piston or cup-washer 27 secured to its lower end and reciprocable in outer cylinder 20. The head 25 may function as a stop for the plunger 27.

The head 25 is also formed with a passageway 28 connecting with air pressure line 24 at one end 10 and communicating with the inner lower end portion of intermediate cylinder 21 when the latter is in extended position, thus enabling air pressure entering said portion to extend the inner cylinder 22.

15 Inner cylinder 22 is provided with a head at its upper end on which the printing base 13 is supported, while the lower end is provided with a piston or cup-washer 30 that is reciprocable in intermediate cylinder 21. The said cylinder 22 is also reciprocable through a head 31 that is in the upper end of the intermediate cylinder 21.

As seen in Fig. 5, air lines 24 communicate between the lower ends of each of the outer cylinders 20 and a common air line 35 that in turn connects with a source 36 of air under pressure. A manual or foot operated valve 37 in said air line 35 connects the outer cylinders with said source 36 when in the position indicated in Fig. 5 or when the valve is rotated a quarter turn the outer cylinders may exhaust to the atmosphere for collapsing under the weight of the printing base to the position shown in Fig. 3.

Air lines 29 communicate with the space between the pistons 27, 30 and a common air line 38 that in turn connects with said source 36. A foot or manually actuatable valve 39 in line 37 is similar to valve 37 and when in the position indicated in Fig. 5 admits air under pressure to below piston 30 for maintaining the cylinder 22 expanded as seen in Fig. 11. A quarter turn of the valve 39 will open the interior of cylinder 21 to the atmosphere permitting the inner cylinder 22 to descend to collapsed position within the intermediate cylinder 21.

45 In actual practice, when the apparatus is ready for printing, the valve 37 is open, thus elevating the printing base to position 15 (Fig. 1) and the valve remains open. The operator then positions a sheet of paper in proper position on the printing base and opens the valve 39, whereupon the base is elevated, bringing the sheet against the screen or stencil carried by the latter. The squeegee is then moved across the screen to force the paint through the latter and onto the sheet that is on the printing base, after which the valve 39 is moved a quarter turn so as to close the line leading to the source of air 36, and open to exhaust the lines 29 leading from the valve to the lower ends of the intermediate cylinders, whereupon the printing frame carrying the printed sheet will be lowered to position 15 (Fig. 1). The operator then merely lifts the sheet 40 (Fig. 7a) onto the rapidly rotating take-off roller 10 that in turn deposits the printed sheet on conveyor 11 for carrying below infra-red drying lamps 41. The conveyor 11 and roller 10 may be driven by any suitable source of power connected with a belt or chain 42 that in turn extends over a pulley 43 supporting one end of conveyor 11, 70 while a suitable belt 44 may connect the pulley shaft 45 with roller 10.

The printing base 13 has upstanding members 46 projecting from its upper side along two adjacent edges of the base for positioning each sheet to be printed in the same position on said

base in or to insure proper register. These members must be retractable or movable downwardly when the base is moved against the printing screen to permit the printing step. Fig. 4 shows the yieldable support for each member 46.

Each member (which is preferably rectangular in horizontal cross-sectional contour (Fig. 2)) extends through a correspondingly shaped opening in said base. A shoulder 47 (Fig. 4) on each member limits the upward movement thereof, and expansion springs 48 connect the lower ends of said members (below the upper surface of base 13) with said base. Thus, as soon as the upwardly projecting ends of the members 46 engage the printing frame, the springs 48 will expand to permit said ends to come flush with the lower side of the frame whereby the sheet on said base will be tight against the printing screen or stencil therebelow. The springs will cause the members 46 to automatically return to the position shown in Fig. 4 when the printing base is lowered.

In order to prevent objectionable shock, expanded coil springs 49 are carried by the printing frame and depend therefrom (Fig. 1). These springs are engaged by brackets 50 (Fig. 4) carried by base 13 just before the printing base reaches the uppermost end of its movement, thus cushioning the blow that would otherwise result from engagement between the printing frame and base when the latter is moved to printing position. An upward projection 51 on each bracket 50 (Fig. 4) is adapted to enter the lower end of each spring 49 when said base frame is in elevated printing position. Other similar springs 52 carried by the intermediate cylinders 21 function for the same purpose.

The printing frame, generally designated 1, comprises marginal frame members 54 (Figs. 8, 10) that may be angle iron strips arranged with one of their sides 55 vertical and their other sides 56 horizontal and extending outwardly relative to the center of the frame. These strips are arranged to provide an oblong or rectangular frame (Fig. 7).

The screen 58 is secured at its marginal portion against the underside of the sides 56 of angle strips 54 by strips 59 that in turn are secured to the inwardly extending sides 60 (Fig. 10) of an outer frame formed of angle strips 61. The other sides 62 of angle strips 61 extend vertically across the outer sides of angle strips 54 and project above the level of the upper edges of the sides 55 of the latter. An outer frame 63 encloses strips 61 and carries the later.

The lower sides 60 of angle strips 61 terminate below the lower sides 56 of angle strips 54 along lines spaced outwardly of the inner sides of the latter strips, thus permitting the printing base to pass into the space defined by the free inner edges of lower sides 60 of strips 64 and into close engagement with screen 58.

The lower sides 56 of angle strips 54 may be apertured at spaced points for passing elements 65 on strips 59 therethrough. These elements are each formed with a horizontal through opening for a wedge 66 (Fig. 12) that functions to tighten strip 59 against screen 58. Upon knocking out the wedges the screen is readily removed for replacement.

The upper edges of angle strips 61 (Figs. 8, 10) that extend along the longitudinally extending sides of the screen frame, form tracks for flanged wheels 70 of the squeegee.

The squeegee itself is generally designated 69.

and comprises a cross member 71 that extends between wheels 70 and over screen 58. This cross member carries the flexible blade 72 (Fig. 9) that engages the screen 58 and that functions to scrape the painting medium over the screen from end to end of the latter during each printing operation. The blade or scraper portion of the squeegee is vertically adjustable toward and away from the screen by means of a screw 73 that threadedly extends through a nut 74 secured to a transversely extending metal strap 75 that is centrally between the ends of said cross member 71. The lower end of screw 73 is rotatably secured to a vertically sliding blade holder 76 (Fig. 9) that receives the upper edge of the flexible blade 72. A spring 78 reacts between the holder 76 and a washer 79 against nut 74 to yieldably hold the holder 76 in expanded position, while a predetermined pressure on the squeegee will cause the latter to move upwardly compressing the spring 78. By turning the screw 73 the blade holder may be moved in one direction or the other axially of said screw until the desired position for best work is obtained. A relatively long handle 79 is secured to the squeegee and projects slantingly upwardly therefrom in the direction of the platform 4 and over the latter so that the operator 6 on said platform can move the squeegee from one end of the printing screen to the other upon walking back and forth on the platform.

The handle 79 is generally of U-shape with the free ends connected to the ends of the squeegee as best indicated in Fig. 8, while the closed end of the U is adapted to be grasped by the hands of the operator as seen in Fig. 1.

At the same points where the free ends of the U-shaped handle 79 connect with the squeegee are laterally projecting arms 81 (Fig. 12) that extend laterally from the squeegee in the same direction as arm 79. Each of these arms carries a roller 82 at its outer end, and each such roller is adapted to engage the upper edge of the side 55 of the angle strips 54 that extend parallel with the angle strips supporting the squeegee (Fig. 13). A brace 83 extends upwardly from the outer end of each arm 81 to the side members of arm 79 to brace the wheels 82.

The provision of said wheels 82 enables the operator to elevate the squeegee, if he so desires, by pivoting the squeegee on the wheels upon moving the handle 79 downwardly.

At the opposite ends of the screen frame are portions 85, 86 that are outwardly beyond the printing portion of the screen. The painting medium on the screen is deposited on one or the other of these end portions according to the position of the squeegee. These portions may be imperforate or may be blocked off by extensions at the ends of the printing base or in any other suitable manner. The important thing is that the paint is held on said portions against going through the screen or frame when the printing base is moved away from the screen frame or vice versa. Such portions are employed in practically all conventional screen printing apparatus.

The present invention provides means for automatically elevating the squeegee over the paint after the latter has been drawn across the screen in one direction and for then causing the squeegee to re-engage the paint upon reversing the directional movement of the squeegee for drawing the paint back across the screen.

The above means comprises a pair of opposingly positioned vertical plates 90 (Figs. 1, 6, 7) posi-

tioned adjacent the vertical sides 62 of the angle strips 61 on which wheels 70 of the squeegee are supported. There is one pair at each of the corresponding ends of the angle strips 61, and each of said plates extends through the upper flange 91 (Fig. 6) of the side frame members 63. The plates 90 are horizontally elongated, and the end of each plate nearest a central point intermediate the ends and frame members 63 is connected to said frame members by a pair of horizontally spaced, vertical, parallel links 94. Said links 94 are pivotally connected at their upper ends to said end of each plate 90 by pivots 95, while the lower ends of said links are connected with frame members 63 by pivots 96. A spring 97 yieldably holds each plate 90 in elevated position against one end 98 of the slot in flange 91, said end being most remote from said links, or adjacent the outer ends of the frame members 63. The upper edge of each plate is parallel with and above the level upper edge of the side 62 of each angle strip 61 on which the wheels 70 are supported. The adjacent ends of the pair of plates at opposite ends of each of said angle strips 61 extend slantingly upwardly as at 99 to said upper edge of each plate, and the tracks formed by said sides 62 of said angle strips extend slantingly upwardly at points 99 adjacent the outer ends of said plates so that the wheels 70 of the squeegee in moving from the screen over said portions 85 or 86 at the ends of the screen, will move upwardly onto the upper edges 100 of plates 90 and then onto the elevated ends 101 of sides 62. Thus the blade of the squeegee will pass upwardly over the supply of paint it has drawn over the screen as soon as the paint is deposited on either of said positions 85, or 86.

The plates 90 are held against the ends 98 of the slots in flanges 91 against downward movement when the wheels 70 run upwardly onto said plates over inclined edges 99. However, upon movement of the squeegee, as soon as the wheels 70 run downwardly over the edges 99 of sides 62 onto the ends of plates 90 that are remote from links 94, the plates 90 will swing downwardly to position the squeegee blade alongside the paint that is on either portion 85, or 86 as the case may be, for drawing said paint across the screen 58 upon continuing the movement in said reverse movement. The operator may, of course, tilt the squeegee carriage at any time about rollers 82 for elevating and lowering the squeegee blade, and the squeegee can be rolled on said rollers in said tilted position as well.

In operation in printing a conventional job on sheets that are, say 34 x 84 inches in size, the operator at position 12 (Fig. 14) may position the printing base in the dash line position 15 shown in Fig. 1. The stencil is placed on the printing base, being properly positioned by the projections 46 that are along the sides adjacent the feed device 9 and the take-off roller 10. The operator then actuates valve 39 for elevating the printing base to a position against the underside of the screen 58. The operator 6 then draws the paint over the upper side of the screen by means of the squeegee 69, thereby causing the stencil to stick to the frame. A sheet of any kind may be between the printing base and the stencil to keep the base clean during the operation of adhering the stencil to the screen.

In some instances parts of the stencil may have to be adhered by hand, or removed, after the first operation above described, and in such instances the operator 12 may lower the printing

base to fully depressed position (Fig. 3) and do the necessary work on the stencil. Once the stencil is ready for doing the necessary job the printing base is again elevated to position 15 (Fig. 1) by actuation of valve 37, and a sheet is drawn from the feed stack at 9 onto said base and positioned by the projections 46. The valve 39 is then actuated and the printing base quickly carries the sheet to the screen, whereupon the operator 6 moves the squeegee across the screen, effecting a printing on the sheet on the printing base. The printing base is then lowered to position 15 and operator 12 quickly lifts it onto take-off roller 10 that quickly deposits the same on conveyor 11 that in turn carries the sheet to below the drying lamps 41.

Another sheet is placed on the printing base and the operation is repeated.

The operator 6 quickly manipulates the squeegee by himself and the operator 12 handles the feeding and removal of the sheets by himself. There is no swinging of a heavy printing frame and squeegee, nor is more than one man necessary for feeding and removing sheets from the machine.

It is to be understood that the invention as described in detail is merely illustrative of the preferred form of the invention and is not necessarily restrictive thereof.

We claim:

1. Screen printing apparatus comprising a horizontal printing frame supporting a screen through which the printing medium is to be forced from above, a flat, substantially rectangular horizontal printing base below said frame for supporting the material to receive the said medium for making the desired imprint, axially extensible vertically disposed telescopic posts supporting said base at points adjacent its four corners for vertical reciprocable movement to and from said frame, means for admitting fluid under pressure into said posts for extending the same for causing said movement to said frame and for exhausting said fluid for permitting collapse of said posts and movement of said base away from said frame, foot controlled valve means below said frame for controlling the flow of said fluid into and out of said posts, and power means along one edge of said base for carrying said material away from said base when said posts are collapsed and said base is spaced below said frame, the laterally projected area of the space between said base and said frame along the edge of said base opposite said one edge thereof being unobstructed for manual manipulation of said material on said base by an operator positioned adjacent said one edge when said posts are collapsed.

2. In screen printing apparatus that includes a rectangular, horizontal printing frame carrying a stencil screen, tracks along two opposite sides of said frame, a squeegee having wheels rotatable on said tracks for supporting said squeegee for movement over the screen longitudinally of said tracks, horizontal end members respectively extending between the corresponding ends of said two opposite sides and adjacent the ends of said tracks for supporting the painting medium to be drawn by said squeegee across said frame when said squeegee is moved from one end of said tracks to the other, a pair of correspondingly shaped elements respectively positioned adjacent corresponding ends of said tracks and projecting above the latter for engaging the wheels of the squeegee and elevating the latter upon said

wheels going over said elements said elements being adjacent said end members whereby said squeegee will be elevated to pass over said medium after the latter is drawn onto said end members, means yieldably supporting said elements in elevated position, stop means for holding said elements elevated against downward movement for so elevating said squeegee when the latter is moved off said screen in direction away from the latter and onto said elements, said elements being movable downwardly away from said stop means and against the yieldable resistance of said means under the weight of said squeegee upon reverse movement of said squeegee in direction toward said screen whereby said squeegee will engage said medium on said reverse movement for drawing the same over said screen.
